UNITED STATES PATENT OFFICE.

REUBEN E. OTTENHEIMER, OF BALTIMORE, MARYLAND.

REFRIGERATOR CONSTRUCTION.

Application filed July 2, 1923. Serial No. 649,084.

To all whom it may concern:

Be it known that I, REUBEN E. OTTENHEIMER, a citizen of the United States, residing at Baltimore city, State of Maryland, have invented certain new and useful Improvements in Refrigerator Construction, of which the following is a specification.

This invention relates to refrigerator construction and more especially to the construction of the door jambs whereby leakage of air between the timbers forming the jambs is guarded against effectually.

One of the objects of the invention is to form a jamb of cooperating stepped sections which, when assembled, contact along tortuous lines so as to provide the maximum resistance to the flow of air between the sections.

A further object is to provide means for drawing the sections together to hold their stepped faces tightly in contact.

With the foregoing and other objects in view which will appear as the description proceeds, the invention consists of certain novel details of construction and combinations of parts which will be hereinafter more fully described and pointed out in the claims, it being understood that various changes may be made in the construction and arrangement of the parts without departing from the spirit of the invention as claimed.

In the accompanying drawing, which is a sectional perspective view of a portion of a refrigerator, the preferred form of the invention has been shown.

Referring to the drawing by characters of reference, A designates the stationary or wall section of the jamb and B designates the adjustable and removable section. The section A includes a face strip 1 to the inner face of which are secured parallel spacing strips 2 and 3 and a bearing strip 4. The strips 2 and 4 are in contact and interposed between the strips 2, 3 and 4 and the face strip 1 is a layer of suitable insulating material such as one or more sheets of paper 5. An air space 6 is provided between the strips 2 and 3 and a strip 7 of fibre insulation is also interposed between said strips. Secured to the strips 2 and 3 and bridging the space 6 is a sheet 8 of paper or other suitable insulating material.

Spaced strips 9 are secured to the strips 2 and 3 and upon the sheet 8 and one of these strips 9 constitutes a bearing or step of the

section A. An inner face strip 10 is secured to the strips 9 and is spaced therefrom by a layer 11 of paper or other suitable insulating material. This strip 10 also constitutes a bearing or step of the section A and projects beyond the alined outer sides of strips 3 and 9 so as to extend into a side finishing strip 12 that is secured to the strips 1, 3 and 10.

The other section, B, of the jamb includes a face strip 13, a beveled abutment strip or wear strip 14 and a stop strip 15 projecting from the inner marginal portion of the abutment strip. In the angle formed by the strips 13 and 14 is secured a group of bearing strips 16, 17 and 18 providing steps, as shown and an inner face strip 19 is secured to the abutment strip 14 and the stop strip 15 and provides an additional step, as shown. A bead strip 20 can be secured to this strip 19 to provide a finish.

A desired number of openings 21 are formed in strip 1 to receive the heads of bolts 22 that are extended through the strip 4 and into the strips 17. Obviously by means of the bolts the section B can be drawn tightly against the section A so that the steps of one section will rest against the steps of the other section and a tight connection provided between the parts. A finishing strip 23 can be secured to strip 1 for the purpose of concealing the bolt holes 21. By removing the bolts or screws 22 the section B can be removed bodily for repairing or replacing the parts. The meeting stepped faces of the sections held together tightly prevents leakage of air through the jamb structure and adds materially to the efficiency of the refrigerator.

What is claimed is:-

1. In a refrigerator construction a door jamb including a stationary section having a stepped face, a removable section having a stepped face, means for drawing together the stepped faces of the two sections, and holding them in contact.

2. In a refrigerator construction a door jamb including a stationary section having a stepped face, a movable section having a stepped face, means for drawing together the stepped faces of the two sections, and a finishing strip for concealing said means.

3. In a refrigerator construction a door jamb including a stationary section comprising a face strip, spacing and bearing

strips secured thereto and insulated therefrom, there being an air space between the spacing strips, additional spacing strips, secured to and insulated from the first named spacing strips, and an inner face strip secured to and insulated from the second-mentioned spacing strips, and a movable section including a face strip, an abutment strip secured thereto, a stop strip upon the

abutment strip, and stepped strips secured 10 in the angle of the face and abutment strips, and means carried by the stationary section and engaging the movable section, for drawing together the stepped faces of the sections. 15

In testimony whereof I affix my signature.

REUBEN E. OTTENHEIMER.
